UNITED STATES PATENT OFFICE.

JOSEPH NÉMETH, OF NEW YORK, N. Y.

DOLL.

1,327,168.

Specification of Letters Patent.

Patented Jan. 6, 1920.

Application filed December 17, 1918. Serial No. 267,129.

To all whom it may concern:

Be it known that I, JOSEPH NÉMETH, a citizen of Hungary, and a resident of the city of New York, in the county of Bronx 5 and State of New York, have invented certain new and useful Improvements in Dolls, of which the following is a specification.

The present invention relates to doll heads, and more particularly to a mechanism 10 for effecting the closing and opening of the eyes, as embodied in what are termed "sleeping dolls," now in common use.

In producing these devices, the doll head is first decorated or painted, and the eye 15 mechanism, as a whole, then inserted into the same and fastened thereto by means of a suitable adhesive. Part of the decorating operation is performed usually by dipping the doll-head into a suitable paint, which 20 would be deposited on the eyes, if the same were previously mounted in the doll-head. In practice, it has also been found that the eye mechanism is apt to become loose or detach itself in time entirely from the doll- 25 head, as the adhesive material does not always form a proper union between the eye mechanism and the doll-head.

The main object of the present invention is to overcome these defects, by so constructing 30 the eye mechanism that the eye-ball supporting bracket is adapted to be securely fixed to the head by suitable fastening means, such as screws, and the said bracket is constructed in such a manner that the 35 eye-ball carrying bridge piece or spindle is adapted to be mounted on the said bracket after the decorating operation.

Another object of the invention is to provide eyes, which are adapted to be adjusted 40 upon the bridge piece connecting the same.

A further object of the invention is to produce a device of the character described, which is simple in construction, efficient in operation, and which can be manufactured 45 on a commercial scale, or, in other words, one which is not so difficult to produce as to be beyond the reasonable cost of such an article.

With these and other objects in view 50 which will more fully appear as the nature of the invention is better understood, the same consists in the combination, arrangement and construction of parts hereinafter described, pointed out in the appended 55 claims and illustrated in the accompanying drawings, it being understood that many

changes may be made in the size and proportion of the several parts and details of construction within the scope of the appended claims without departing from the 60 spirit or sacrificing any of the advantages of the invention.

One of the many possible embodiments of the invention is illustrated in the accompanying drawings, in which:—

Figure 1 is a vertical central section taken through a portion of a doll-head, showing the device as applied; Fig. 2 is a rear elevation of the eye mechanism; Fig. 3 is a perspective view of the supporting bracket 70 of the eye mechanism; Fig. 4 is a section taken on line 4—4 of Fig. 2, the bracket being omitted to more clearly show the construction; and Fig. 5 is a section taken on line 5—5 of Fig. 4, on a larger scale, the 75 bracket being also omitted.

In the drawings, the numeral 10 indicates the front section of the head of a doll, provided with the eye mechanism. The head has eye openings 11, and may be made of 80 any suitable material, such as for instance bisque, wax or papier-mâché. The eyes 12 comprise each a substantially hemi-spherical shell 13, made, for instance, of metal and provided with a horizontally extending 85 slot 14, that extends from the rear face of the shell to a plane beyond the center thereof. Each of these shells is drawn over a spherical body 15, made for instance of cork. These bodies fit snugly the shells, the latter being shiftable on said bodies, for a purpose hereinafter to be described. The eyes are connected by a horizontally extending bridge piece 16, made preferably of wire, the ends of which extend through the 90 slots 14 into the spherical bodies 15. To prevent a shifting of the spherical bodies 15 on the bridge piece 16, a substantially U-shaped wire clamp 17 is provided, the base 18 of which extends parallel to the 100 bridge piece 16, while its legs 19 are passed into the spherical bodies 15, as clearly shown in Fig. 5 of the drawings.

To the bridge piece is attached centrally a downwardly extending arm 20, carrying a 105 weight 21 at its lower end. The upper end of the arm 20 is bent upwardly and rearwardly, as shown at 22, to limit, in co-operation with a stop 23, the tilting movement of the eyes. The stop 23 is disposed above the 110 eye openings and secured in any suitable manner to the inner face of the doll-head.

The bridge piece 16 is rotatably mounted in a bracket 24, that is secured at its lower end by screws 25 to a projection 26 on the interior of the doll-head. This bracket is made of a suitable springy material and extends centrally upward to the eye openings 11, where it is provided with a central substantially vertically extending slot 27, thereby forming a fork-shaped structure, each 10 prong 28 of which is bent forwardly and thence back upon itself rearwardly, so as to constitute bearing members for the bridge piece 16. Both rearwardly extending prong portions 29 are at their rear ends bent somewhat downward, as shown at 30, and thence upward as appears at 31. The diameter of the bridge piece 16 is such that, in inserting it into the bearing members of the bracket 24, the rearwardly bent prong portions 29 must first be forced upward, snapping back as soon as the bridge piece has passed the portions 30 of the same, whereby the bridge piece is kept in proper position upon the bracket 24. The slot 27 in the bracket 24 permits of a relative motion between the latter and the arm 20.

Upon the outer face of the weight 21 is mounted a cork abutment 32, that is adapted to come into contact with the lower portion 30 of the bracket 24, to limit the movement of the eyes in one direction. In the other direction the movement of the eyes is limited by the stop 23 above referred to, upon which is mounted a cork piece 33, that comes into 35 contact with the extension 22 of the arm 20.

The eye mechanism is assembled in the following manner: The bracket 24 is secured by the screws 25 to the section 10 of the head before the two sections, constituting 40 the same, are united. After the uniting operation, the head is decorated as above specified. The eyes 12 are mounted upon the bridge piece 16 and adjusted to the distance between the eye openings 11 before the 45 U-shaped wire clamp 17 is passed into the spherical bodies 15. The bridge piece with the elements thereon is then inserted into the head, and engaged with the bearing members of the bracket. The bridge piece 50 and the eyes are thus rotatably mounted

upon the bracket so that, when the doll is in its upright position, the pupils painted or otherwise represented upon the eye-balls register with the eye openings. When the doll is laid down, the weight 21, acting in 55 conjunction with the arm 20 as a pendulum, causes the bridge piece 16 and the eyes attached thereto to swing around, or in other words it "closes" the eyes. When the doll is returned to upright position, the eyes are 60 brought to normal "open" position.

The shells 13 are adapted to be shifted angularly upon the spherical bodies 15, so that the eyes may be adapted to the eye 65 openings.

It is obvious that, while herein the invention has been illustrated in connection with a doll-head, it is equally adapted for use in connection with toy puppets, representing 70 animals, etc.

It is also to be observed that instead of the cork bodies 15, spheres of such other suitable materials may be employed, which permit of a convenient insertion of the bridge 75 piece and the U-shaped clamp 17.

What I claim is—

1. An eye mechanism for doll-heads including two eye members, each of which comprises a substantially hemi-spherical shell constituting the exterior of the eye, and a spherical body over which said shell is drawn, a bridge piece connecting said eyes consisting of a spindle having its ends extending through said shells into the bodies therein, and a clamping piece connecting 85 said spherical bodies.

2. An eye mechanism for doll-heads including two eye members, each of which comprises a substantially hemi-spherical shell constituting the exterior of the eye, and a spherical body over which said shell is drawn, a bridge piece connecting said eyes consisting of a spindle having its ends extending through said shells into the bodies 90 therein, and a U-shaped clamping piece connecting 95 said spherical bodies.

Signed at New York, in the county of New York and State of New York, this 22nd day of November, A. D., 1918.

JOSEPH NEMETH.
